UNITED STATES PATENT OFFICE.

HENRY L. DOHERTY, OF NEW YORK, N. Y.

APPARATUS FOR REMOVING SUSPENDED LIQUIDS AND SOLIDS FROM GASES.

1,034,216.

Specification of Letters Patent. Patented July 30, 1912.

Application filed December 31, 1909. Serial No. 535,643.

To all whom it may concern:

Be it known that I, HENRY L. DOHERTY, a citizen of the United States, and a resident of New York city, in the county of New York and State of New York, have invented certain new and useful Improvements in Apparatus for Removing Suspended Liquids and Solids from Gases, of which the following is a specification.

10 My invention relates to an apparatus for removing suspended liquids and solids from gases, and particularly to a type of such apparatus in which the gaseous current is caused to follow a spiral path.

15 The object of my invention is to provide means for separating from a gaseous current substantially all of the suspended liquid and solid particles which it contains with special reference to the removal of tar 20 and dust particles from illuminating gas.

In my invention which is the subject of Letters Patent No. 798,667, dated Sept. 5, 1905, I have revealed an apparatus for accomplishing the above object by passing the 25 gaseous current through a helical passage at a rapid rate, whereby a rapid rotary motion is given to the current and the suspended liquid and solid particles thrown off by the centrifugal force, so developed. This present

30 invention embodies an improvement on the one, which is the subject of the Letters Patent mentioned, by virtue of which I am enabled to communicate a whirling motion to the gas current, while permitting each

35 particle thereof, theoretically, to travel always in the same horizontal plane. By this method and apparatus, I am enabled to separate the suspended matter from the gas by the utilization of centrifugal force, and, 40 at the same time, avoid the relatively high pressure that is requisite for carrying out this method in my former apparatus.

In the accompanying drawings, Figure 1 is a vertical diametrical section through the 45 apparatus on the line A B of Fig. 2. Fig. 2 is a horizontal, cross-section through the same on the line C D of Fig. 1. Fig. 3 is a part elevation of the apparatus showing the method of suspending the lift of the apparatus and the water and pressure gages, etc. Fig. 4 is a detail of the water gage showing the manner in which it is connected. Fig. 5 is a plan of the apparatus showing the blower or exhauster according to which 50 means is used to communicate the necessary velocity to the gas. Fig. 6 is an enlarged

vertical section of the upper part of the tar extractor, showing the device for supplying the liquid, when there is none, or at least a deficiency, in the gas itself. Fig. 60 7 is an enlarged horizontal section through the top of the extractor showing a top view of the liquid-supplying-device.

In the several figures, 1, designates the outer vessel of the apparatus, which is simply a fixed cylindrical tank with the addition of the various gas and liquid connections, gages, etc.

2, designates the vertically-movable bell or lift, which works within 1, and contains 65 the device for communicating the whirling motion to the gas current.

3, designates the spiral partition or wall forming the gas passage through 2.

4, in the design shown, is the gas inlet 75 pipe, 5 the gas discharge pipe. 6, the semi-cylindrical sheet fastened to 1 to form an enveloping chamber, 6', for the gas inlet 4.

7, is the cross beam resting on columns 8, 8', which support the pulleys 9 and 9' over 80 which the rope or chain 10 supporting the bell-chamber, 2, passes. One end of this chain, 10, is attached to the ring 11 of the bell-chamber, 2, and the other is fixed to a counterweight, 12.

85 13, is a water gage indicating the liquid level in the bell-chamber 2, and 14 is the corresponding pressure gage. 15, is a U-connection from the gages to the interior of the gas inlet-chamber 6'.

90 16, is the connection from the gage 13 to the liquid in tank 1.

95 17, is a connection for introducing the liquid for the seal, when starting up the apparatus.

18 is the liquor discharge pipe for drawing off the liquor when desired.

100 19, is the tar well in which the tar collects owing to the fact that its specific gravity is heavier than that of the ammoniacal liquor in the apparatus.

105 20, is the tar discharge pipe, having a valve 21, through which the tar separated from the gas is discharged.

The method of operation of the particular apparatus shown is as follows: The seal in 1 having been brought up to the proper level, and the counterweight 12 weighted to the point that will have just sufficient unbalanced weight, to the bell-chamber 2, to exert the pressure on the gas requisite to force it through the usual condensing and purify-

- ing apparatus, the valves 22 and 23 on the gas inlet and discharge passages, respectively, are opened and gas flows through the gas inlet pipe 4 to the gas-distributing chamber 6' formed by the sheet 6. As shown, the pipe, 4, projects well above the surface of the liquid seal in 1. The relative depths of the lift and liquid seal are so adjusted that, in its highest position, the gas passages of the lift are under a seal corresponding to the maximum pressure to which the gas will be subjected in the separator. Any suitable stopping device may be provided to prevent the lift 2 from being forced out of its seal by an abnormal gas pressure. In the present design of apparatus it is arranged that the cross-beams 7 will engage and stop the motion of 2 when the latter is at its highest permissible position. The gas passes from 6' to the outer termination of spiral passage 25, thence through the successive convolutions of 25 until it enters last convolution enveloping the gas-collecting chamber 24 of the lift 2. This, as shown, is formed by a pipe, 24', fastened to the top of 2 and so set that it envelops more or less of the upper part of the gas outlet 5 as the lift 2 rises and falls. Perforations, 24" in 24', enable the gas to pass from 25 to 24. The gas discharges from 24 through the discharge pipe 5. In passing through the spiral passage 25 the gas is subjected to an angular velocity which gradually increases in intensity from the periphery to the center of the lift. The centrifugal force thus developed throws the liquid and solid particles suspended in the gas to the periphery of the gaseous current, and therefore against the outer wall of the spiral passage. This is always wet with a film of liquid (tar, when the gas passed through the apparatus is crude illuminating gas) which immediately seizes upon the particles (dust or globules of tar, ammoniacal liquor, etc.) and retains them. As the separated matter accumulates, it runs down the vertical spiral wall and into the liquid seal at the bottom. Here the tar being of higher specific gravity than the water and ammoniacal liquor collects in the tar well 19. It may be drawn off either continuously or intermittently through the pipe 20.
- If, during the operation of the apparatus, the volume of gas passing through the same should increase above the normal the tendency would be to build up the pressure in the chamber 2. Since, however, this is counterweighted, the result of the increased flow of gas is, simply, to raise the chamber 2, as the flow of gas increases, the free area of the gas passages increasing, of course, with the upward movement of the chamber 2. Since the area of the gas passages through the apparatus thus keeps pace with the increase in the flow of the gas, the pressure

remains substantially constant at the normal gas pressure for the apparatus. Owing to the design of the apparatus, variations in the flow of gas, within the limits for which the apparatus was designed has absolutely no effect upon the efficient working of the separator. Since the differential pressure between inlet and outlet remains, substantially, constant the velocity of the gas passing through the separator is also constant; and, as the separation of the gas and suspended matter depends mainly upon the velocity, the efficiency of the apparatus is evidently independent of the volume of gas passing.

The spiral passage 25 for the attainment of the highest efficiency of operation should be quite narrow. While I do not limit myself to this dimension, I consider that a cross-dimension of the spiral passage of 85 from 1½ to 2 in. gives the best results. With a narrow passage, such as this, a comparatively short travel will suffice to substantially free the gas from suspended matter. By thus passing the gas through the apparatus in a comparatively thin sheet all the particles of the gaseous current are sure to be brought in contact with the wall of the passage.

A blower, 26, connected with the gas inlet pipe by a passage, 27, imparts the necessary velocity to the gas. By connecting 27 with both the suction and discharge pipes of the blower I can, at my option, operate the separator either under induced or forced draft. Also, I can pass the gaseous current either from the center to the periphery, or vice versa, as may be preferred. It is evident, also, that by shifting the blower suction connection to the pipe 5, I can establish an induced draft from the periphery to the center of my separating chamber. It is to be understood, that I do not limit myself to either direction of flow of the gaseous current through the separator, or to working with either forced or induced draft. As long as the necessary differential of pressure, between the gas inlet and outlet to my separator to give the necessary velocity to the gas is secured, it is evident that, within ordinary ranges of pressure, it is a matter of comparative indifference whether the actual pressure happens to be above or below atmospheric. I prefer to pass the gaseous current from the periphery to the center of my separator as I thereby subject the current to a gradually increasing angular velocity, and consider that I can work with less back pressure for an equal maximum angular velocity, communicated to the gas current, than when passing the gas from center to periphery.

In the foregoing description, I have considered, simply, the application of my invention to the removal of suspended matter

from a gas, which itself carries sufficient liquid to coat and carry out of the gas solid particles in suspension. When, on the other hand, I wish to remove suspended dust from a gas (or air current) or treat a gas containing much solid and little liquid matter in suspension, I supply the deficiency in liquid to the surface of the vertical wall of the spiral passage through the flexible hose 28, to the spiral liquid-distributing pipe 29. This pipe has numerous small perforations 30, in its bottom and is coiled in the spiral passage as shown, the interior extremity of 29 being capped. The liquid discharging from perforations 30 falls onto the deflecting plate 31, which is fastened to the spiral wall, 3, of the gas passage, with spacers, 32, separating it from actual contact with the wall, leaving a narrow opening between 31 and 3 through which the liquid flows in contact with 3. By this means I am able to secure a uniform film of liquid on 3 and with any given dimension of 29 and 30, can evidently secure regulation of the quantity of film-forming liquid supplied, by regulating the pressure at which the liquid is supplied through 28. Filtered tar is, I find, well adapted for the film-forming liquid, but it is manifest that any other liquid may be substituted therefor, if preferred.

Having described my invention, what I claim is:

1. An apparatus for separating from a gaseous fluid particles suspended therein which comprises in combination a gas holder comprising a tank member and a lift member a continuous spiral passage in said lift member, an outlet for gaseous fluid at the center of said passage and an inlet for gaseous fluid at the outer termination of said spiral passage.

2. An apparatus for separating from a gaseous fluid, particles suspended therein, which comprises in combination a gas holder comprising a tank member and a lift member, a substantially, vertical, continuous spiral partition fastened to the top of the said lift and its lower edge terminating in the sealing liquid contained in the tank member of said gas holder, whereby a continuous spiral passage is formed from the inner periphery of the lift to the axis of the same, an outlet for gaseous fluid at the axis of the lift and an inlet for gaseous fluid at the inner periphery of said lift.

3. An apparatus for separating from a gaseous fluid, particles suspended therein, which comprises in combination a gas holder comprising a tank member and a lift member, a substantially vertical continuous spiral partition attached to the top of the lift of said gas holder and its lower edge terminating in the sealing liquid in the tank of said gas holder, whereby a continuous spiral passage is formed from the inner

periphery of said lift to the axis of the same, an inlet for gaseous fluid at the periphery of said lift and an outlet for gaseous fluid at the axis of said lift, and a receptacle for tar in communication with the lower part of the tank of said gas holder.

4. An apparatus for separating from a gaseous fluid, particles suspended therein, which comprises in combination a gas holder having a substantially, vertical perforated pipe attached to the top of the lift of the same and its lower extremity sealed by the sealing liquid in the tank of said gas holder, a continuous spiral partition having its inner convolution enveloping said perforated pipe and the extremity of its outer convolution attached to the shell of said lift, the upper edge of said partition being attached to the top of said lift and its lower edge terminating in the sealing liquid in said tank, whereby there is formed a continuous spiral passage through the space inclosed by said lift from said axial perforated pipe to the inner periphery of said lift, an inlet for gaseous fluid communicating with the outer convolution of said spiral passage and an outlet for gaseous fluid communicating with the said perforated pipe.

5. An apparatus for separating from a gaseous fluid, particles suspended therein, which comprises in combination a gas holder having a substantially vertical perforated pipe attached to the top of the lift of the same and its lower extremity sealed by the sealing liquid in the tank of said gas holder, a continuous spiral partition having its inner convolution enveloping said perforated pipe and the extremity of its outer convolution attached to the shell of said lift, the upper edge of said partition being attached to the top of said lift and its lower edge terminating in the sealing liquid in said tank, whereby there is formed a continuous spiral passage through the space inclosed by said lift from said axial perforated pipe to a place on the inner periphery of said lift, a projecting extension of the shell of said lift inclosing a chamber which is in communication with the outer convolution of said spiral passage, a projecting extension of the wall of the tank of said gas holder which corresponds in position with and is adapted to envelop more or less of the said projecting extension of the shell of said lift according to the position of said lift, a gas passage passing through the bottom of the tank of said gas holder at the axis thereof, and projecting above the sealing liquid in said tank, said gas passage being of smaller cross-section than said axial perforated pipe and adapted to "telescope" with said perforated pipe, a gas passage likewise passing through the bottom of the tank of said gas holder, and terminating above the sealing liquid in said tank, said gas passage

- being of smaller cross-section than the chamber formed by the shell of said lift, and so located with reference to such chamber that it projects into said chamber, a receptacle for tar communicating with the bottom of said tank, a pipe for withdrawing tar from said receptacle, means for introducing sealing liquid into said tank and means for withdrawing surplus liquid from said tank.
6. In combination, an open-top tank adapted to hold a sealing liquid, an open-bottom tank of smaller cross-section than said open-top tank, said open-bottom tank being adapted to "telescope" with said open-top, a counter-weighting device attached to said open-bottom tank, means for introducing gas into said open-bottom tank and means for discharging gas from said open-bottom tank, a spiral gas passage within said open-bottom tank connecting said gas-introducing means with said gas-discharging means, and a draft-producing means, connected to the interior of said open-bottom tank for the purpose of producing a draft through the spiral passage of said open-bottom tank.
7. In an apparatus for separating suspended matter from a body of gaseous fluid, the combination of a draft-producing means to impart motion to said body of gaseous fluid, a spiral passage of constant length but variable cross-section, means for automatically varying the cross-section of said spiral passage according to the volume of gas flowing therethrough, and means for withdrawing from said spiral passage the matter separated therein from the body of gaseous fluid passing therethrough.
8. An apparatus for separating from a gaseous fluid particles suspended therein which comprises in combination, a gas-holder, comprising a tank member and a lift member, a continuous spiral passage in said lift member, means for supplying a film of liquid to the outer wall of said spiral passage, an inlet for gaseous fluid at the outer termination of said spiral passage and an outlet for gaseous fluid at the central termination of said spiral passage.
9. An apparatus for separating from a gaseous fluid particles suspended therein, which comprises in combination a gas holder having a substantially vertical continuous spiral partition fastened to the top of the lift of the same and its lower edge terminating in the sealing liquid in said gas holder, whereby a continuous spiral passage is formed from the inner periphery of said lift to the axis of the same, a spiral perforated pipe located in the upper part of said spiral passage and following the convolutions of the same, a deflecting plate attached to the wall of said spiral passage but not in contact with said wall, below said spiral perforated pipe, and means for supplying liquid to said spiral perforated pipe, an inlet for gaseous fluid at the periphery of said lift and an outlet for gaseous fluid at the axis of said lift, and a receptacle for tar in communication with the lower part of the tank of said gas holder.
10. In an apparatus for separating suspended matter from a body of gaseous fluid, the combination of a draft-producing means to impart motion to said body of gaseous fluid, a spiral passage of constant length but variable cross-section, means for supplying liquid to the outer wall of said spiral passage, means for automatically varying the cross-section of said spiral passage according to the volume of gas flowing therethrough and means for withdrawing from said spiral passage the matter separated therein from the body of gaseous fluid passing therethrough.
11. In an apparatus for separating from a gaseous fluid, matter suspended therein, the combination of a spiral passage, a gas conduit connected to the central extremity of said spiral passage, a gas chamber in free and unobstructed communication with the peripheral extremity of said spiral passage, and means for automatically varying the free cross-sectional area of said spiral passage according to the volume of gas flowing therethrough.
12. In an apparatus for separating from a gaseous fluid, matter suspended therein, the combination of a spiral passage having the spiral wall thereof, substantially vertical, a gas conduit connected to the central extremity of said passage, a gas conduit connected to the peripheral extremity of said passage, and means for varying the free area of the cross-section of said passage according to the volume of gas flowing therethrough.
13. In an apparatus for separating from a gaseous fluid, matter suspended therein, the combination of a cylindrical chamber, having a substantially vertical continuous spiral partition fastened to the top of said cylindrical chamber but terminating above the bottom of said chamber, whereby a continuous spiral passage is formed from the center to the periphery of said chamber, a gas conduit connected to the central extremity of said passage, means for automatically varying the free area of said spiral passage according to the volume of gas passing therethrough, a gas-chamber in free and unobstructed communication with the peripheral extremity of said spiral passage, and a gas conduit connected with said gas chamber.
14. In an apparatus for separating from a gaseous fluid, matter suspended therein, the combination of a spiral passage, means for supplying a liquid to the outer wall of said

passage to form a substantially continuous sheet or film on said wall, gas conduits connected to the peripheral and central extremities of said spiral passage, respectively, and means for varying the free area of said spiral passage according to the volume of gas passing therethrough.

15. In an apparatus for separating from a gaseous fluid, matter suspended therein, the combination of a spiral passage having the spiral wall thereof substantially vertical, means for supplying a liquid to the outer wall of said passage, a gas conduit con-

nected to the peripheral extremity of said passage, a gas conduit connected to the central extremity of said spiral passage, and means for varying the free area of the cross-section of said passage according to the volume of gas flowing therethrough.

Signed at New York city in the county 20 of New York and State of New York this 30th day of December A. D. 1909.

HENRY L. DOHERTY.
